UNITED STATES PATENT OFFICE.

JOHN G. WEBB, OF RICHMOND, VIRGINIA.

MOLD FOR PLURAL CASTINGS.

1,389,722.

Specification of Letters Patent. Patented Sept. 6, 1921.

Application filed January 5, 1920. Serial No. 349,386.

To all whom it may concern:

Be it known that I, JOHN G. WEBB, a citizen of the United States, residing at Richmond, in the county of Henrico, State 5 of Virginia, have invented certain new and useful Improvements in Molds for Plural Castings; and I do hereby declare the following to be a full, clear, and exact description of the invention, such as will enable others skilled in the art to which it 10 appertains to make and use the same.

This invention relates to the art of casting metals and while it has particularly to do with the casting of relatively small ingots of one hundred pounds or less, the apparatus and process are applicable to heavier work.

The difficulties involved in the casting of small steel ingots by methods and with the 20 means in common practice, together with the expense involved, has led to the adoption of the plan of casting large ingots and breaking them down into lighter billets, except in case of small ingots cast from crucibles, in which case the ingots are cast in vertical position, one ingot at a time, a method that is too slow in the handling of 25 large quantities of molten metal.

Several methods of group pouring have 30 been employed, but those with which I am familiar are unsatisfactory for the manufacture of very small steel ingots because of excessive quantities of discard metal in the long runners employed, because of expense due to the complicity and number of 35 runner bricks, iron bases or retaining flasks for the molds and similar adjuncts and because of the labor and handiwork involved, all increasing the ultimate cost of the product. In practising the present invention, 40 the various adjuncts that determine the expense of first cost, are greatly reduced as is also the expense of manipulation. The runner bricks are comparatively few, the runners are short and can be shaped to constitute 45 an additional shape or ingot and no retainer flasks are necessary. The molds are simply set up on a plane surface, as herein-after explained.

The use of molds such as hitherto employed, has necessitated an expenditure of 50 time and labor in the stripping and resetting that is largely obviated by the novelty of mold and the method of handling herein-after explained.

In the drawings:

Figure 1 is a perspective view showing what may be termed an H form of mold employed by me, looking at its closed end.

Fig. 2 is an elevation of the open end of 60 the mold shown in Fig. 1.

Fig. 3 is a perspective view showing a plurality of molds assembled at each side of a runner brick, with the combined lifter and carrier bars associated with them. 65

Fig. 4 is a section on line 4—4 of Fig. 3.

Fig. 5 is a section on line 5—5 of Fig. 3.

Fig. 6 is a longitudinal horizontal section through the runner shown in Fig. 3.

Fig. 7 is an elevation showing the group 70 of molds undergoing the process of stripping of the ingots from them.

Fig. 8 is a view similar to Fig. 3, showing the molds laid up in a plurality of tiers.

Fig. 9 is a view similar to Fig. 1, showing 75 what may be termed a U form of mold.

Fig. 10 is a view similar to Fig. 5, illustrating the manner of assembling molds shown in Fig. 9.

Fig. 11 is a view similar to Fig. 3 and 80 showing a plurality of tiers of molds disposed to radiate from the runner.

Fig. 12 is a section on line 12—12 of Fig. 11 illustrating the use of the H type of mold. 85

Fig. 13 is a perspective view showing a vertical arrangement of molds, the runner and the connected portions of the molds being in sectional perspective.

Fig. 14 is an elevation illustrating a different manner of discharging the ingots. 90

Referring first to Figs. 1 to 5 inclusive of the drawings there is employed a runner brick 20 having a central longitudinal passage 21 from which lead at regular intervals the laterally directed gates 22, the passage 21 terminating short of the ends of the runner brick. Midway of the ends of the brick is a pouring gate 23 formed through its upper wall and with which is 95 engaged the usual sink head 24.

In connection with the runner brick 20 there is employed at each side a series of molds 25, which in the arrangement shown in Fig. 3, consist each of a rectangular body 100 having in two of its opposite longitudinal faces the longitudinal channels 27 that extend through one end of the mold and terminate short of the opposite end. Thus the mold, except at the portion beyond the 110

closed ends of the channels, is substantially of H shape as shown in Figs. 1 and 2. In setting up the molds there is provided a supporting frame including a pair of cast iron horses *a* disposed parallel upon the suitable casting floor and transversely of which intermediate of their ends, is secured a channel iron *b*, opening downwardly. Parallel with the channel iron *b* and at each side of it is arranged upon the horses *a*, the angle bars *c*, near to the ends of the horses. The runner brick is placed upon the channel bar, extending longitudinally of it, and, as illustrated, is narrower than the channel iron so that there is a rest formed by the channel iron at each side of the runner brick. The molds are disposed at both sides of the runner brick, with their inner end faces in contact with the brick and with their inner end portions supported upon the channel iron, while their outer end portions rest upon the angle bars *c*. The molds are disposed with their central web portions 26 vertical and their longitudinal channels 27 opening horizontally. It will be noted that the channels 27 have their side walls diverging outwardly, short of the other end and with the arrangement of molds as shown in Fig. 3, the runner brick 20 serves to close these open ends, while the longitudinal channels 27 register in pairs, excepting with respect to the endmost molds of the series at each side of the runner brick. The result is a plurality of substantially octagonal prismatic mold 35 forms at both sides of the runner brick and each communicating with the longitudinal channel 21 of the runner brick through a gate 22.

With the arrangement just described it will be understood that metal poured through the sink head and into the runner brick, will pass through the several gates 22 and into the forms of the molds, with resultant ingots, the several mold members of each series being at such time held in closely assembled relation by means of a clamp that includes the jaw plates 28 and connecting tie rods 29 that are threaded at their ends to receive the clamping nuts 30.

To facilitate removal of the ingots from the molds, each mold at its closed end is provided with an eye 31, the openings of which register to receive a combined lifter and carrier bar 32. After the metal has cooled, hooks 33 with suitable tackle attached, are engaged with the bar 32 where it projects beyond the molds and the corresponding ends of the molds are lifted, at which time the sagging of the inner ends of the molds causes the ingots to break from the runner so that each series of molds, through the medium of its bar 32 and the connected hooks, may be raised and swung to suitable supports 34 upon which the end portions of the bar 32 are rested with the

molds between them, all as shown in Fig. 7 of the drawings. The clamp is then removed from the molds and a mold at one end of the series is slid along the bar 32, when the ingot will drop from its longitudinal channel and the associated channel of the next mold. The next mold is then slid along the bar against the first mold so that the next and corresponding ingot drops. This process is continued until all of the molds have been shifted laterally with the discharge of their ingots and the reassembling of them in mutual contact. The clamp is then returned to place to hold the molds securely together as formerly and, through the medium of the hooks and tackle, the bar with the molds is lifted and returned to position upon the plane supports. The other series of molds at the opposite side of the runner is then similarly manipulated, when a new runner core or brick is adjusted to position between the series of molds for a repetition of the operation.

It will of course be understood that by forming the channel 21 of the runner brick of the proper shape and with proper dimensions, the runner metal may constitute a usable shape.

Referring now to Fig. 8 of the drawings there is illustrated a plurality of equipments of molds and runner bricks with the arrangements shown in Fig. 3, the equipments being disposed one upon another in tiers and the pouring gates being continued in registration through the lower walls of the bricks so that all of the molds may be filled at a single pouring. When the metal has solidified, the series of molds with their ingots may be broken from the runners and the ingots discharged as previously described. In this arrangement, a single clamp, including plates 28' and upper and lower bars 29', is provided for the entire number of molds at each side of the vertical series of runner bricks 20 and in practice, wooden wedges *d* are driven between the plates 28' and the endmost molds of each horizontal series, to firmly hold them together.

Referring to Figs. 9 and 10 of the drawings there is shown a mold 35 having in one side face the longitudinal channel 36, the side walls of which diverge to the said side face, as do the walls of the channels of the molds previously described. The channel 36 extends through one end of the mold and terminates short of the other end. As shown in Fig. 10, these molds 35 are assembled with their faces vertical and with the channeled face of one against the opposite, unchanneled face of another, it being understood that their positions with respect to the runner brick, are the same as in the case previously described. These molds are also provided with eyes 31' at their closed ends

to receive a bar for manipulating the mold in the same manner as previously described in connection with the **H** type of molds.

5 In Fig. 10, the manner of clamping the molds together similar to the manner illustrated in Fig. 5, is shown but without the supports.

In Figs. 11 and 12 of the drawings is shown an embodiment of the invention in which there is employed a central, hollow runner brick 40 that is closed at its lower end through the medium of a plate *e* upon which it rests, this core or brick being cross-sectionally rectangular and having gates 41 in its side walls. The core or brick being rectangular in cross-section, the gates are thus disposed in a plurality of horizontal series, each including four gates. The series 20 of gates are equally spaced vertically of the brick.

In connection with the brick 40 there is employed a plurality of vertical series of molds 42 which are illustrated of the **H** type and which series correspond in number to the sides of the brick. The molds 42 are laid up with their webs horizontal and the open ends of their longitudinal channels 43 in the direction of the core brick, which 30 is vertical, as illustrated. The molds being disposed in vertical series, one upon another, the upper channel of each mold, excepting the uppermost one, co-operates with the lower channel of the mold next above, 35 to constitute a mold form, with each of which communicates a gate of the runner brick. Upon the upper end of the runner brick is arranged a sink head 44.

Each mold is provided at its closed end 40 with an eye 45 which opens in the direction of the side opening of the mold channels so that when the molds are assembled as illustrated, these eyes will register vertically to receive a carrying and suspending bar 46. 45 After the cast has been made, at which time the poured metal passes from the runner brick to the forms of the several molds, each series of molds is picked up by means of a tackle connected with the bar 46 and is 50 hung from the bar by placing it upon supports in the same manner previously described. The molds are then separated successively to discharge the ingots and rearrange the molds in mutual contact, ready to 55 be returned and again assembled with a new runner brick for another cast.

It will of course be understood that while the runner brick is illustrated as four sided, the number of its sides may be increased or 60 diminished to accommodate a corresponding number of mold series.

The closure plate *e* projects laterally in all directions beyond the runner brick and supports the inner end portions of the series of 65 molds, there being provided an additional

supporting plate *f* for the outer end portion of each series of molds. These plates *e* and *f* are carried by a supporting cross-shaped frame *g* that holds the molds above the level of the casting floor.

In Fig. 13 of the drawings, there is shown an arrangement of molds 50, of the **H** type that are disposed vertical with their open ends upwardly and having supported thereon a runner brick 51 from the central longitudinal channel 52 of which lead gates 53, each to a pair of co-operating longitudinal channels 54 of a pair of molds. The pouring gate 55 is through the opposite wall of the brick from the gates 53 and there is associated with it a sink head 56. At the lower or closed ends of the molds 50 are the eyes 57 that register with each other to receive a carrying and supporting bar 58, the molds themselves being disposed between suitable sills 59 to support them with the eyes out of contact with the surface upon which the arrangement is erected. The pouring operation is of course apparent while the manner of stripping the ingots 90 from the molds is the same as that previously described.

It will of course be understood that either the **H** type or the **U** type of mold may be employed in each of the various arrangements 95 illustrated while the runner brick in each instance forms also a mold to produce a usable shape.

It will also be understood that a clamp may be employed for holding together the 100 molds of the series in each instance.

In Fig. 14 of the drawings, there is illustrated another equipment for discharging the ingots from the molds. In this equipment, instead of passing a bar such as 32 in Fig. 7, through the eyes 31, there is employed a spreader bar 60 to which is connected the lifting chains 61 and from which depend at regular intervals, the hanger chains 62 having hooks 63 at their lower ends that engage the eyes 31, respectively. The spacing of the hanger chains 62 is slightly greater than the spacing of the eyes 31 when the molds are in ingot-receiving positions. Thus, when the bar 60 is lifted, the individual molds are suspended from it through the medium of the chains 62 and they swing apart by gravity, this separation of the molds permitting the discharge of the ingots 63', as will be understood. In Fig. 14 115 all of the ingots excepting one have dropped from their molds. It will be, of course, understood that after the discharge of the ingots by this method, the molds may be returned to the mold floor and again set up 120 with whatever specific arrangement is desired.

What is claimed is:

1. A composite mold comprising a runner brick having a plurality of outlet gates, and 130

- a plurality of mold members having each a plurality of like mold faces and associated with each gate and providing a mold form arranged to receive from that gate, the association of mold members at each gate including a like mold face of a mold member of another association.
2. A composite mold comprising a runner brick having a plurality of outlet gates and a plurality of like, reversible mold members having each a plurality of mold faces, the mold members being reversible for association of either of its mold faces with either of the mold faces of another member, a plurality of mold members being associated with each gate in position to provide a mold form in receptive relation to that gate, the association of mold members at each gate including a mold face of a mold member of another association.
3. A composite mold comprising a runner brick having a plurality of outlet gates and a plurality of like mold members having each a plurality of like separated mold faces and associated with each gate in position to provide a mold form in receptive relation to that gate, the association of mold members at each gate including a like mold face of a mold member of another association.
4. A composite mold comprising a plurality of superimposed runner bricks having each a plurality of outlet gates and a plurality of superimposed series of mold members, the members of each series having each a plurality of mold faces and associated with each gate of the corresponding runner brick and providing a mold form arranged to receive from that gate, the association of mold members at each gate including a mold face of a mold member of another association, and means common to all of the runner bricks for feeding metal to them.
5. The combination with a separable series of plurally coöperative mold members, of a carrier member with which they are connected for successive separation to discharge their casts while connection with the carrier member is maintained.
6. The combination with a separable series of mold members constructed and arranged to coöperate plurally to constitute separate mold forms, each mold form including a mold member of the adjacent form, of a carrier bar with which the mold members are slidably connected for separation of the mold members of each coöperative plurality with a simultaneous assembly of a mold member with a mold member of the previously separated plurality to constitute a mold form.
7. The combination with a series of mold members each having a hanger eye, of a rod with which the hanger eyes are slidably engaged for movement of the mold members toward and away from each other, the mutually adjacent faces of mutually adjacent mold members being formed to jointly effect a mold form.
8. A composite mold comprising a vertical runner brick having a vertical series of laterally directed gates, a vertical series of runner bricks communicating at their ends with corresponding gates of the vertical brick and having each a horizontal series of gates and a mold form associated with each gate of each horizontal runner brick, each of said mold forms comprising a plurality of like mold members each with a plurality of like, separated, mold faces and each mold form including a mold face of a member of an adjacent mold form.

In testimony whereof, I affix my signature, in the presence of two witnesses.

JOHN G. WEBB.
